[57] ABSTRACT

Baffles disposed transversely of a coke quenching car and one end wall have apertures therein that are of different geometric shapes and are progressively larger in size toward said locomotive. Hot coke falling into compartments formed by the baffles illuminates the apertures so that the operator recognizes into which compartment the coke is falling.

COKE QUENCHING CAR ALIGNMENT INDICATING SYSTEM

BRIEF SUMMARY OF THE INVENTION

An improvement in a coke quenching car includes at least one traverse baffle therein and an end wall having apertures of different geometric shapes and progressively larger size toward a locomotive wherein there is an operator; such apertures being disposed along a line of sight of the operator.

For a further understanding of the invention and for features and advantages thereof, reference may be made to the following description and the drawing which illustrates a preferred embodiment of equipment in accordance with the invention.

BRIEF DESCRIPTION OF THE DRAWING

In the drawing:

FIG. 1 is a schematic perspective view of a coke quenching car that incorporates an embodiment of the present invention;

FIG. 2 is a view along the line of sight indicated in FIG. 1 before pushing of coke commences; and

FIG. 3 is a view along the line of sight of FIG. 1 during one stage of pushing.

DETAILED DESCRIPTION

In order to control the emission of smoke and dust to the atmosphere during the pushing of hot, incandescent coke from a coke oven chamber, there has been developed apparatus for collecting and removing effluent emitted while pushing coke, as described in co-pending application Ser. No. 170,926, filed Aug. 11, 1971.

Such apparatus includes a hood mounted to a coke guide car and horizontal covers and an adjustable pair of curtains that are mounted to the hood to cover compartments formed by baffles in the quenching car and thereby prevent the emission of smoke and dust during pushing.

Because the covers and the hood prevent visual inspection of the coke as it is being pushed, there is a need for some means to indicate when the compartments of the coke quenching car are full. The quenching car locomotive operator will then know how fast or how slow to move the quenching car to insure uniform coke distribution therein.

Referring to FIG. 1, there is shown a schematic arrangement of a quenching car 11 connected to a locomotive 13 wherein there is an operator who controls the locomotive 13 and car 11 manually by means of controller 15.

The quenching car 11 is shown in position for receiving hot incandescent coke falling through a hood 17. The hood 17 has horizontal covers 19, 21 and curtains 23 like those described in the aforementioned application.

The car 11 has three internal baffles 25, 27, 29 and end walls 31, 33, that divide the car interior into four coke compartments numbered 1, 2, 3, 4. The baffle 25 has in it a triangular opening 35; the baffle 27 has in it a circular opening 37; the baffle 29 has a hexagonal opening 39; and the end wall 33 has a rectangular opening 41.

The several openings 35, 37, 39, 41, as shown, have regular geometric forms, and they are disposed along a line of sight 43 that the operator would observe as he

looks through a window 45 in the front end of the locomotive 13. The rectangular opening 41 is the largest opening; the hexagonal opening 39 is smaller than the rectangular opening 41, but is larger than the circular opening 37 which is larger than the triangular opening 35. Hence, before pushing commences, the operator looking along line of sight 43 and sees the several opening shapes as shown in FIG. 2. They would appear as dark images.

Now, when pushing commences, the operator will observe a red triangular shape, indicating that hot, incandescent coke is falling into compartment No 1. The operator waits approximately 5-10 seconds to allow compartment No. 1 to fill and then he actuates the controller 15 to move the locomotive 13 and car 11 in the direction of the arrow A.

When the illuminated red triangle changes to an illuminated circle, as suggested in FIG. 3, the operator knows that the hot incandescent coke is falling into compartment No. 2. He then continues to move the car and observes that the illuminated circle changes to a hexagon as coke falls into compartment No. 3 and the illuminated hexagon changes to an illuminated rectangle when coke begins to fall into compartment No. 4.

From the foregoing description of one embodiment of the invention, those skilled in the art should recognize many important features and advantages of it, among which the following are particularly significant:

That the invention is simple and involves a minimum first cost to install in a coke quenching car; That there are no maintenance expenses in using the invention; and that there are no training expenses for an operator of the quench car locomotive. A simple diagram of the several geometric figures, displayed on the locomotive window and numbered to correspond with the compartments.

Although the invention has been described herein with a certain degree of particularity it is understood that the present disclosure has been made only as an example and that the scope of the invention is defined by what is hereinafter claimed.

What is claimed is:

1. In a coke quenching car having end and side walls connected endwise to a locomotive having an operator therein, the improvement comprising:
  - a. at least one transverse baffle subdividing said car into two coke-receiving compartments said baffle having an aperture disposed along a line of sight observed by said operator; with
  - b. the end wall of said car adjacent said locomotive having therein an aperture that is larger than the aperture in said baffle and that is disposed along said line of sight.
2. The invention of claim 1 wherein:
  - a. said aperture in said baffle has a regular geometric form.
  3. The invention of claim 1 wherein:
    - a. said aperture in said baffle has a regular geometric form; and
    - b. said aperture in said end wall has a regular geometric form that is larger and different from the aperture in said baffle.
  4. The invention of claim 1 wherein:
    - a. said quenching car has a plurality of baffles having in each baffle an aperture along said line of sight,

with said apertures increasing progressively in size in the direction toward the locomotive.

5. In a coke quenching car having end and side walls connected endwise to a locomotive having an operator therein, the improvement comprising:

- a. at least one transverse baffle subdividing said car into two coke-receiving compartments;
- b. said baffle having an aperture of regular geometric form disposed along a line of sight observed by said operator;
- c. the end wall of said car adjacent said locomotive having therein an aperture of regular geometric form, but larger in size than the aperture in said

baffle and disposed along said line of sight.

6. In a coke quenching car having end and side walls, adapted for movement by a locomotive actuated by an operator therein, the improvement comprising:

- 5 a. a plurality of baffles transversely disposed in said quenching car, each said baffle and the end wall of said car nearest said locomotive having an aperture of regular geometric shape disposed along a line of sight observed by the operator, said apertures increasingly progressively in size toward said locomotive.
